UNITED STATES PATENT OFFICE

156,548

KITCHEN UTILITY CABINET

Paul B. Maunde and Oscar E. Gilmer, Dallas,
Tex.; said Gilmer assignor of one-fourth to Leander W. Hedrick, Dallas, Tex.

Application December 1, 1947, Serial No. 142,890

Term of patent 7 years

(Cl. D33—19)

To all whom it may concern:

Be it known that we, Paul B. Maunde and Oscar E. Gilmer, citizens of the United States, residing at Dallas, in the county of Dallas and State of Texas, have invented a new, original and ornamental Design for a Kitchen Utility Cabinet, of which the following is a specification, reference being had to the accompanying drawing, forming a part thereof.

The single figure is a front perspective view of a kitchen utility cabinet, showing our new design.

We claim:

The ornamental design for a kitchen utility cabinet, as shown.

PAUL B. MAUNDE.
OSCAR E. GILMER.
